USPC **D8/44; D8/312**

CLAIM

The ornamental design for a cable tie tensioning and cut-off
tool knob, as shown and described.

(58) **Field of Classification Search**

DESCRIPTION

USPC D8/14, 14.1, 29.1, 29.2, 30, 44, 51, 61,
D8/68, 312; 292/336.3, 347; 16/101.1,
16/412, 414-20, 443-446, 441, 110 R,
16/111 R

FIG. 1 is a front left side perspective view of the cable tie
tensioning and cut-off tool knob;

CPC B25B 25/00; B26D 7/08; B26D 7/14;
B65B 13/027; E04F 21/162; G06K 7/10881

FIG. 2 is a rear left side perspective view of the cable tie
tensioning and cut-off tool knob;

See application file for complete search history.

FIG. 3 is a left side, elevation view;

FIG. 4 is a right side elevation view;

FIG. 5 is a top plan view thereof;

FIG. 6 is a bottom plan view thereof; and,

FIG. 7 is a rear elevation view thereof.

The broken lines in the drawings illustrate features and linear
detail that form no part of the claim.
